UNITED STATES PATENT OFFICE.

EDWARD R. OWEN, OF NYACK, NEW YORK.

HOLDER FOR RECEPTACLES.

Application filed May 5, 1925. Serial No. 28,197.

This invention relates to improvements in holders for receptacles and more particularly to means for holding an oil can on an automobile,—one object of the invention being to 5 so construct a can holder that it shall be readily attachable to a fixed part on the automobile, preferably to the engine so as to be enclosed therewith by the hood.

A further object is to so construct the holder that the can shall be held against displacement and prevented from rattling.

A further object is to construct a can holder in such manner that it shall be adaptable for the reception of cans of different shapes and 15 sizes.

With these and other objects in view, the invention consists in certain novel features of construction and combinations of parts as hereinafter described and pointed out in the 20 claims.

In the accompanying drawings,—

Figure 1 is a perspective view of a holder embodying my improvements, and

Figure 2 is a sectional view.

25 My improved holder embodies a frame 1 which may be conveniently of strap iron, and a depending yoke or supporting member for a can,—said yoke or supporting member being indicated at 2 and having its upper end portions secured to the central portions of the respective side members of the horizontal frame 1. One arm of the centrally located yoke or supporting member 2 is bent laterally at its upper end to provide a laterally projecting arm or ear 3 having a perforation 4. This arm or ear may be inserted between the head of one of the bolts which secures the engine head in place and said head,—said bolt passing through the hole in the ear or arm 3. One 30 end of the strap forming the frame 1 may be provided with a lateral projection 5 and an angle piece may be secured to the upper end of one of the yoke arms to provide a lateral projection 6 parallel to the projection 5 and through these lateral projections, a screw 7 is passed and provided with a thumb nut 8 to be turned home against the projection 5, by which means the frame may be clamped about a can. I prefer however to employ clamping 35 devices both in the horizontal frame and in the yoke to hold the can against displacement. Thus a clamping screw 9 is passed through one end of the frame and provided with a head 10 to engage the can,—said screw being retained against movement by means of a thumb nut 11, and the screw may also be provided

with a thumb turn 12. A similar screw 13 having a head 14 at its inner end, passes through one of the vertical members of the yoke and is provided with a thumb turn 15 and a clamping nut 16. If desired, sprung clamps 17 to engage sides of a can may be located within the depending yoke portions of the holder.

The frame 1 and one of the yoke arms are 40 so shaped that they will accommodate a square can or an elongated can. When an elongated can is used, its bottom may rest upon the bottom 18 of the yoke and one of its ends may be engaged by the head on the 45 clamping screw 9 and holding arms attached to respective end members of the horizontal frame and having lips 19 at their upper ends may be snapped over upper edge portions of the can. Should a can be used which is 50 smaller than the distance between two ends of the frame, a cross bar 20 may be inserted 55 between parallel sides of the frame 1 near one of the end cross-bars of the latter,—said cross-bar having studs at its respective ends 60 to enter openings in the frame sides,—one of 65 said openings being in the form of a slot for the accommodation of a movably mounted holding member 21 for said cross-bar. The holding member 21 is provided with a 70 threaded shank 22 which receives a thumb nut 23, whereby said holding member may be 75 clamped in place. In order to adapt the device to receive a square can, the horizontal 80 frame 1 is made with a lateral bulge 24 and 85 one arm of the yoke may be bent to provide 90 a shoulder 25 upon which the bottom of the square can may rest.

Should it be found desirable to secure a can (either elongated or square) against possibility of vertical movement, a bail may 95 be provided to extend over the top of the can and against two sides thereof. This bail may comprise an angle member 26 having its depending arm hinged as at 27 to the frame 1 and a depending member 27¹ hinged as at 28 to the horizontal portion of said angle member, said depending member 27¹ being provided at its lower end with a lateral ear 29 disposed parallel with the lateral ear 30 on the frame, said lateral ears being removably secured together by a clamping screw 31 and nut 32 thereon.

Having fully described my invention what I claim as new and desire to secure by Letters-Patent, is:

1. A holder of the character described

comprising a horizontal frame having an intermediate offset portion in one side, a yoke secured to and depending from the side members of the frame and provided with a horizontal shoulder below the offset portion of the frame, and clamping means carried by the yoke and the frame to engage a side and an end of a can supported by the yoke within the frame.

10 2. A holder of the character described comprising a horizontal frame, a cross bar, means for securing the cross bar within the frame near and spaced from one end thereof, means at the opposite end of the frame for 15 clamping a can against the cross bar, and a yoke secured to and depending from the sides

of the frame to support a can received within the frame.

3. A holder of the character described comprising a horizontal frame, a yoke secured to and depending from the sides of the frame, an angle member disposed above the frame in vertical alinement with the yoke and hinged at one end to the yoke and one side of the frame, a terminal member hinged 20 to the opposite end of said angle member, and means for securing the free end of the terminal member to the yoke and the frame. 25

In testimony whereof, I have signed this specification.

EDWARD R. OWEN.
